US00D830326S

(12) **United States Design Patent** (10) Patent No.: **US D830,326 S**
(45) Date of Patent: ** Oct. 9, 2018

(54) **PHONE**

(71) Applicant: **SHENZHEN ROYOLE TECHNOLOGIES CO., LTD.**, Shenzhen (CN)

(72) Inventors: **Qi Lin**, Shenzhen (CN); **Yijun Shi**, Shenzhen (CN); **Chao Jiang**, Shenzhen (CN); **Jianlei Zhu**, Shenzhen (CN)

(73) Assignee: **SHENZHEN ROYOLE TECHNOLOGIES CO., LTD.**, Shenzhen (CN)

(**) Term: **15 Years**

(21) Appl. No.: **29/568,157**

(22) Filed: **Jun. 15, 2016**

(30) **Foreign Application Priority Data**

Dec. 16, 2015 (CN) 2015 3 0536437

(51) LOC (11) Cl. **14-03**

(52) U.S. Cl.

USPC **D14/147**; D14/248

(58) **Field of Classification Search**

USPC ..... D14/248, 130, 140, 140.7, 140.8, 142, D14/144, 147, 148, 149, 150, 155, 158, D14/159, 168, 188, 217, 226, 229, 240, D14/250, 329, 466-468, 496, 299, 138 R, D14/138 AA, 138 G, 341; D21/517

CPC H04M 1/00; H04M 1/003; H04M 1/02; H04M 1/03; H04M 1/04; H04M 1/21

See application file for complete search history.

(57) **CLAIM**

The ornamental design for a phone, as shown and described.

DESCRIPTION

FIG. 1 is a front view of a phone showing my new design; FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in FIG. 6 depict portions of the phone that form no part of the claimed design.

1 Claim, 3 Drawing Sheets
